UNITED STATES PATENT OFFICE.

LOUIS FREDERICK RUDSTON FELL, OF FOWTHORPE, FILEY, ENGLAND.

MEANS FOR ABSORBING POWER AND DETERMINING THE REACTION ON ENGINES.

1,369,018.

Specification of Letters Patent. Patented Feb. 22, 1921.

Application filed July 31, 1918. Serial No. 247,695.

To all whom it may concern:

Be it known that I, LOUIS FREDERICK RUDSTON FELL, a subject of the King of Great Britain, residing at Fowthorpe, Filey, 5 England, in the county of Yorkshire, have invented new and useful Improvements in and Relating to Means for Absorbing Power and Determining the Reaction on Engines, of which the following is a specification.

This invention has reference to absorbing power and determining the reaction on engines more particularly when the engine is run at different speeds and developing different horse powers. The object of this invention is to determine the amount of reaction exerted on the engine bearers, especially aero engine bearers, with variations in engine load.

The invention therefore consists in absorbing the power developed by an engine at various speeds by a controllable flow of air and measuring the reaction of the absorbed power on said engine.

This invention contemplates a variable air 25 brake for absorbing the power developed by the engine to be tested in combination with an engine support responsive to variations in torque reaction due to variations in load on the engine and means for measuring that 30 reaction.

In order that the invention may be readily understood and carried into effect same will now be described more fully with reference to the accompanying drawings in which:—

Figure 1 is an elevation of an embodiment of the invention in which provision is made in the device for two valved outlets for air.

Fig. 2 is a side view with the test bench and engine bearer adjacent thereto.

Fig. 3 is an elevation illustrating an arrangement involving a single valved outlet for air.

Fig. 4 is an elevation and Fig. 5 a side view illustrating a further arrangement in which air set in motion by the engine is utilized in cooling the engine.

According to the embodiment illustrated in Figs. 1 and 2 a casing *a* which may be constructed of wood built up on a suitable 50 framework and lined with sheet metal is provided having suitably disposed air outlets *b b* whereof the effective area is controlled by appropriate valves *c c*. The casing incloses a chamber *d* preferably of snail 55 like form as shown by the dotted lines from which the outlets *b b* extend the said cham-

ber being conveniently formed by the sheet metal lining or composed of wood slats closely arranged and secured so as to render the walls of the chamber approximately air 60 tight. The valves *c* may be operated by mechanism under a single control or each valve may be controlled separately. Preferably the valves are connected so as to be simultaneously opened or closed either manually, mechanically or otherwise. In the arrangement shown each valve *c* is of butterfly form and consists of wings or flaps mounted on a shaft or spindle *e* to each of which latter a lever *f* is secured. These levers *f* are each connected by a rod *g* with a bell-crank lever *h* which carries an extension *i* provided with a nut *k* adapted to be operated by the screw spindle *l* to which the operating wheel *m* or a suitable handle 75 is applied. Mounted in the aforesaid chamber is a suitable fan-brake *n* adapted for being secured to the crank shaft of the engine to be tested so as to be driven thereby or to be driven through appropriate intermediate gearing as may be found convenient according to the type of engine under test. The said fan-brake when rotated in the chamber of the casing causes air which is admitted thereto in any suitable manner 80 such as by means of the aperture or apertures *o* therein through which the crank shaft of the engine passes to flow through the said chamber and through the aforesaid outlets *b b*.

The casing may be formed with suitable doors on one or both sides to afford access to the interior of the casing and the fan-brake if and when required.

In constructing the fan-brake the dimensions are calculated or determined by appropriate formulæ in such a manner as to render it capable of absorbing the maximum power which the engine under test is likely to develop at the lowest number of revolutions per minute at which it is desired to run.

In operation the improved method and apparatus are employed in conjunction with an ordinary balance bar torque reaction test 105 bench indicated at *p* the power absorbed by the fan-brake being adjusted that is to say decreased or increased by either closing or opening more or less the aforesaid valves *c c* the reaction of the power absorbed by 110 the fan-brake being calculated from the balance bar *q* of the torque bench in the usual

- manner by the standard formulæ. Thus the air which is drawn into the casing by the action of the fan is caused to flow from the said casing in a regulated manner with the result that the power developed by the engine and absorbed by the fan-brake reacts upon the engine under test and this reaction is calculable upon the balance bar pertaining to the torque bench.
- 10 For use with the aforesaid apparatus a test bench whereof the engine bearers on the cradle are adapted for being moved relatively to the axis of the fan-brake has been found most convenient as such arrangement 15 renders the test bench capable of adaptation to any type of aero engine.

A construction in which a single controlled outlet for air is employed is illustrated in Fig. 3. The various parts of the 20 apparatus bear reference letters similar to the respective parts in Figs. 1 and 2 and therefore the operation will be clearly understood without detailed description thereof. This arrangement is serviceable in 25 cases where the test bench is so arranged that the torque of the engine tends to effect the rotation of the engine about the axis of the fan-brake and in connection therewith it will be seen that the valve actuating wheel 30 *m* and screw spindle *l* operate directly upon a nut *k* carried by the arm *i* operatively connected with the lever *h*.

The arrangement of valve actuating levers and rods may be duplicated one set being 35 disposed on each side of the fan casing.

If an air cooled engine be under test a part of the air set in motion by the operation of the engine may be diverted so as to serve in cooling the cylinder heads. An arrangement of the apparatus adapted for accomplishing this object is shown in Figs. 40 4 and 5 *a* being the casing *b* the outlet with controlling valve *c* and *d* the snail form of air chamber. A flue or conduit *r* is arranged in communication with the chamber *d* and outlet *b* the said conduit being appropriately formed or curved as seen in Fig. 5 so as to direct the diverted air from the said chamber *d* on to the cylinder head 45 50 of the engine (not shown) which is supported by the test bench *p*.

For convenience of transport the appa-

ratus may be mounted upon a carriage *s* supported by running wheels *t*. Thus it may be moved from place to place with ease as 55 required.

The improved means for testing is especially adapted for use with aero engines as the strains to which the crank shaft of the engine under test is submitted are only 60 those which will be borne by the said shaft during the operative service of the engine, the stress ordinarily sustained by the shaft from revolving a rotor in an inelastic medium such as water when a water brake is 65 used being avoided.

What I claim and desire to secure by Letters Patent of the United States is:—

1. The combination with a fan brake and means for regulating the volume of air 70 passing therethrough for absorbing the power developed by an engine, of an engine bench rotatable about the axis of the fan brake and responsive to variation in torque reaction, due to the power absorbed, and 75 means for measuring that reaction.

2. The combination with an engine, of a fan coupled thereto, a snail-like casing in operative relationship to said fan, a central air inlet opening in said casing, peripheral 80 air outlets in said casing, valves for controlling the flow of air through said outlets to regulate the power absorbed by said fan, an engine support rotatable about the axis of said fan, means for securing the engine 85 to said support and a balance bar mounted on said engine support whereby the torque reaction due to the power absorbed is measured.

3. The combination with a fan coupled 90 to an engine under test, of a casing for said fan, means for regulating the volume of air passing through said casing for absorbing the power developed by the engine a conduit appropriately formed with a depending outlet adapted to conduct the diverted air from 95 said casing on to the cylinder head of the engine, a movable support for the engine responsive to variations in the torque reaction due to absorbed power and means 100 mounted on the engine support for measuring that reaction.

LOUIS FREDERICK RUDSTON FELL.
